UNITED STATES PATENT OFFICE.

FREDERIC GEORGES BAUGATZ, OF PARIS, FRANCE.

ABDOMINAL BELT.

1,230,650.

Specification of Letters Patent. Patented June 19, 1917.

Application filed November 16, 1915. Serial No. 61,817.

To all whom it may concern:

Be it known that I, FREDERIC GEORGES BAUGATZ, a citizen of the Republic of France, residing in Paris, France, have invented 5 certain new and useful Improvements in Abdominal Belts, of which the following is a specification.

The present invention relates to abdominal belts, and it proposes, briefly, an improved article of the general character specified which may be worn either as a support for the abdomen, or, in the manner of a corset, as a means to reduce flesh and to hold up or support various pieces of clothing.

15 The invention aims primarily to provide an abdominal belt, as above described, which will exert a uniform pressure on all portions of the abdomen; which will remain in place without creasing or riding up; and 20 which, in contradistinction to the elastic bandages now in use, can be readily washed.

According to the invention, and for the purpose of effecting the afore-mentioned objects, the improved belt is composed of several 25 parts or pieces, the piece or pieces to be applied directly to the abdomen being made of non-elastic material so as to retain its original shape in spite of use. This abdominal section is formed with a slit, which 30 extends downward from the central portion of the upper edge of said section, and is closed by a flap or tab, the arrangement being such that the belt may easily be loosened or tightened, whenever desired, by

35 merely unfastening or fastening the flap. The various parts or sections of the belt are connected together by button-hole fastenings, which likewise enable the length of the belt to be readily adjusted by changing 40 the position of the buttons, and which permit the belt to be washed without becoming stained, as is the case when metal buckles are used. Also, these button-hole fastenings avoid the unsightly bulges usually caused by 45 straps and buckles.

In the accompanying drawing:

Figure 1 is an elevation of one form of the improved belt;

Fig. 2 is a view, on a greatly-reduced scale, showing the belt in use; and

Fig. 3 is an elevation of a development or modification of the form shown in Fig. 1.

Referring more particularly to said drawing, *a* indicates the front section or member 55 of the belt, which, in this instance, is in-

tended to be worn by a man. The said part *a* is designed to be applied directly against the abdomen, and is constructed of cloth, canvas or other suitable non-elastic, washable material. It may be made either in 60 piece, as shown in Fig. 3, or in two separate parts, as shown in Fig. 1; and in the latter case, the two parts are symmetrical, and are connected together along their inner vertical edges by means of buttons and button-holes *j*. In either case, however, the aforesaid part *a*, when complete, is wider at its middle than at its ends, so as to extend downward and thus cover the entire abdomen; while, preferably, it does not cover the 70 hips.

When made in one piece, the part *a* is provided with a vertical opening or slit *g*, which extends downward from the central portion of its upper edge. This slit may 75 be closed, when it is desired to tighten the belt, by means of a flap or tab *h*, which is retained in closed position by a button-hole fastening *k*, but is adapted to be unbuttoned to loosen the belt. The two-piece 80 construction may likewise be partly or completely buttoned up for the same purpose.

In order to stiffen the part *a*, whether of one-piece or two-piece construction, and cause it to keep its shape vertically, without creasing or riding up, suitable vertical and oblique whalebones or steels *b* and *c* are provided, these bones or steels being arranged symmetrically, as shown.

The part *d* at the back of the belt, is designed to lie against the back of the wearer, as will be understood, and is preferably in the form of a comparatively-narrow strip of non-elastic, washable material, likewise stiffened by whalebones or steels *f*, arranged 95 symmetrically with respect thereto. The adjacent ends of the parts *d* and *a* are connected together by elastic straps or members *e*, which serve to cover the sides of the wearer, three such members being shown in 100 each case. These elastic members have their ends detachably secured to the ends of the parts *d* and *a*, by means of button-hole fastenings, which not only enable them to be removed when it is desired to wash the said 105 parts *d* and *a*, but which also permit the length of the belt to be readily adjusted by merely changing the position of the buttons. Furthermore, the aforesaid fastenings preserve and improve the lines of the figure of 110

the wearer by completely avoiding bulging, which is usually present when belts with strap-and-buckle fastenings are worn.

A belt constructed as above described, fulfills all requirements, and, when worn, exerts a uniform pressure on all parts of the abdomen, the drawing effect produced by the back part *d* and the pressure imposed upon the hips being practically negligible, while there is no liability of the belt losing its shape. It may be utilized to hold poultices or compresses in place, or to support surgical dressings, in which latter case, however, a pad or dressing band would be substituted for that part of the belt which covers the wound. Finally, the belt may be used to support either outer or under garments, according as it is worn over or beneath the shirt, and in furtherance of that purpose may be provided with a slit or hole, *i*, through which may be passed one or another of the buttons of the garment to be supported.

The invention is obviously not limited to the precise structural details illustrated, since it is susceptible of modification and

change within its legitimate scope as hereinafter claimed.

I claim as my invention:—

An abdominal belt acting as a corset, comprising a non-elastic abdominal section having its central portion of greater width than its end portions; a comparatively-narrow, non-elastic back section; and elastic side sections between the abdominal and back sections; said side sections and abdominal and back sections having detachable button- and button-hole fastenings connecting their adjacent ends; and said abdominal section being provided with a slit extending downward for a distance from the central portion of its upper edge, and with button- and button-hole fastening means for closing said slit, to enable the abdominal section to be alternatively tightened or loosened about the abdomen of the wearer.

In testimony whereof I have affixed my signature in presence of two witnesses.

FREDERIC GEORGES BAUGATZ.
